UNITED STATES PATENT OFFICE.

WILLIAM TAYLOR, OF PITTSBURG, PA., ASSIGNOR OF TWO-THIRDS TO
ISRAEL C. PERSHING AND SIMEON BISSELL, BOTH OF SAME PLACE.

MACHINE FOR MAKING WIRE NAILS.

SPECIFICATION forming part of Letters Patent No. 273,190, dated February 27, 1883.

Application filed April 4, 1882. (No model.)

To all whom it may concern:

Be it known that I, WILLIAM TAYLOR, of Pittsburgh, in the county of Allegheny, and in the State of Pennsylvania, have invented certain new and useful Improvements in Machines for Making Wire Nails; and I do hereby declare that the following is a full, clear, and exact description thereof, reference being had to the accompanying drawings, and to the letters of reference marked thereon, making a part of this specification.

This invention relates to improvements on machinery which is designed for the manufacture of wrought-iron and steel nails from round or angular wire or rods; and the nature of my invention consists in certain novel mechanism for automatically feeding forward the nail rod or wire, forming burrs or teeth on the same, gripping the rod or wire, heading the same, pointing, and knocking the finished nails from the machine, which operations are performed successively and with great rapidity upon cold metal, as will be fully understood from the following description, when taken in connection with the annexed drawings, in which—

Figure 1 is an elevation of one side of my improved machine, with the balance-wheel removed and a portion of the main shaft broken off. Fig. 1^a is a side elevation of one of the levers for actuating the reciprocating gripping-bar, also showing the lifting-spring and the cam on the main shaft for vibrating this lever, and a portion of the bed of the machine. Fig. 2 is an elevation of the front of the machine. Fig. 3 is a plan view with a portion of the bed of the frame broken away. Fig. 4 is a top view, enlarged, of the springs and their frame, by means of which the header receives its forward or active strokes. Fig. 5 is a face view of one of the heads between which the header-springs are confined. Fig. 6 is an end view of the cross-head of the spring-frame. Fig. 7 is a vertical longitudinal section of the feeding and burr or tooth forming devices applied to their reciprocating carriage, and also shows a wire, the guide thereof, and part of the frame-bed. Fig. 8 is a view of the burr or tooth forming devices in detail. Fig. 9 is a rear view of what I denominate the "tool-box," showing the gripping and pointing tools therein. Fig.

10 is a vertical longitudinal section taken centrally through Fig. 9, on line *xx*. Figs. 11 and 12 are views of one of the gripping-tools detached from the box of Figs. 9 and 10. Fig. 13 is a view in detail of part of the header, 55 showing the cam on the main shaft, which, acting against the lug on the header, gives the backward strokes thereto, compressing the springs, which shoot it forward to form a head on a nail. Figs. 14, 15, 16, and 17 are perspective views and cross-sections of four different kinds of nails which may be produced by my improved machine. Fig. 18 is a vertical longitudinal section through Figs. 9 and 10. Fig. 19 is a perspective view of one end of the 65 cutting-bar *N*.

Similar letters of reference indicate corresponding parts in the several figures.

In the drawings hereto annexed, *A* designates the bed or top of the main frame of the 70 machine, which is constructed in a rigid substantial manner and cast with suitable bearings and guides for the parts which it is adapted to receive and support.

B designates the main driving-shaft, which 75 is journaled in the frame *A* near its rear part, and which has keyed on one end a balance-wheel, *B'*, and a loose and a fast belt-wheel. (Shown in Fig. 2.)

On that end of the main rotating shaft *B* 80 opposite the end bearing the fly or balance wheel *B'* a circular slotted box or plate, *a*, is rigidly secured by forging or otherwise, and in the slot of the plate *a* is a block which bears a wrist-pin, and which is adjustable by means 85 of a screw, *a'*, for giving more or less eccentricity to the said wrist-pin with respect to the longitudinal axis of the main shaft *B*.

On the wrist-pin one end of a connecting-rod, *B*², is applied, the opposite end of which 90 is applied to the free end of a short arm, *C'*, which is keyed on a horizontal rock-shaft, *C*, located at the front of the machine, and having its bearings in hangers depending therefrom, as shown in Figs. 1 and 2.

It is obvious that the rocking motion of the shaft *C* can be increased or diminished to a nicety by adjusting the wrist-pin more or less eccentric to the axis of the main shaft.

I also key an arm, *C*², on the rock-shaft *C*, 100

the upper end of which is suitably connected to the bottom of a slide, D, that receives a reciprocating motion in a right line in the direction of the length of the main frame, the length 5 of the motion given to this slide determining the length of the nails to be made.

D' designates a stationary upright plate, in which is inserted a removable but fixed eyepiece, b, having a hole or eye through it of a 10 size and shape adapted to serve as a guide and director for the wire on its way to the nail-forming devices. After passing through the eye b the wire passes freely through a plate, e, on the slide D, thence over a steel 15 block, c', suitably secured to a raised part of the slide D, and thence between two peculiarly spurred wheels, d d', hereinafter explained.

Directly above the steel block c' is a vertical plate, e, the lower edge of which is beveled 20 to an acute edge, as shown in Fig. 7, and adapted to bite upon the nail-wire when the slide D is moved forward, and thus move the nail-wire forward the proper length to form a nail. When the slide D is moved back the 25 biting-plate e will slip freely over the nail-wire. This biting-plate e is rigidly secured to ears e⁴, which are pivoted at f to standards rising from the slide D, and to a vertical extension, e', of said ears a screw-threaded pin, g, is applied, 30 one end of which passes freely through the plate c and receives an adjusting-nut, g', on it.

Between the vertical extension e' and the plate c a spring, g², is coiled around the pin g and compressed more or less by adjusting the 35 nut g'. The spring g² will thus act to hold the biting-plate e down on the nail-wire with sufficient force to feed this wire forward at every forward stroke of the slide D, but will yield and allow the plate e to slide freely over the 40 nail-wire during the back-strokes of said slide.

The lower one of the wheels d d' is allowed to turn on a fixed bearing which is rigidly secured to a standard, E, bolted to the slide D, and movable with it. The upper wheel, d', is 45 free to turn on a bearing, which is vertically adjustable by means of a screw in a slot formed in the standard E. The peripheries of the wheels d d' are beveled toward a plate, E', and teeth are formed on these wheels, which are 50 considerably pitched, and so shaped as to form burrs or ribs or teeth on the nails, which give them a firm hold in the wood in which they are driven. The wheels d d' rotate and impress the burrs into the nail-wire during the 55 recession of the slide D; but when this slide is moved forward to feed the nail-wire to the gripping, cutting off, and pointing and heading devices the wheels d d' are inert.

F designates what I denominate a "tool-box," which is rigid upon the frame-bed A, and arranged in advance of the feeding and burring devices above described. Through the front plate of this tool-box the nail-wire passes freely, and first passes between gripping-bars G G' and then between two pointing-bars, N N. Before the pointing-bars are

brought into action to point and cut off a nail, a header, J, is shot forward and forms the head on the nail while it is confined between the gripping-bars G G'. After the head is 70 formed and the pointers recede laterally a knocking-lever is brought into play and discharges the finished nail from the machine. The gripping-bars have impressions made on their steel-faced inner ends, which indent the 75 nail-wire, and thus positively prevent it from slipping during the heading operation, and also during the recession of the slide D. The gripping-bar G abuts against the square head of a screw, G², which is tapped through the block 80 L of the frame-bed A, and is provided with a jam-nut, i. By adjusting this nut the gripping-bar G can be moved up to or from the gripping-bar G', as circumstances may require. The gripping-bar G' is moved away from the 85 gripping-bar G by means of a coiled spring, j, and this bar is moved up to the bar G by means of a wedge, k, on the front end of a lever, M. This lever is of angular form, and it has its fulcrum at l on standards rising from 90 and cast on the frame A. The rear end of lever M is acted on by a single-throw cam, m, on the main shaft B, which at proper times causes the wedge k to move forward the gripping-bar 95 G' and grip the nail-rod. A spring, s, (shown clearly in Fig. 1^a), lifts the front end of lever M and keeps the anti-friction roller at its rear end down.

N N designate the pointing and cutting-off bars, which have their bearings in vertically-adjustable boxes F' F', and which are moved outward, or from each other, by means of springs s' s', and at proper times are forcibly brought together by means of wedges w w, (said wedges being carried on levers W' W', 105 actuated at the proper time by cams on shaft B), acting on adjustable push-bars p p. The boxes F' F' are vertically adjustable by means of screws n n, and the push-bars p p are adjustable by means of nuts o o. (Shown in Fig. 110 3.) The pointing ends of the bars N N have vertical cutting-edges, from the centers of which diverge radial cutting-edges formed by beveling the ends of these bars.

It is obvious that chisel-edged nails may be 115 formed by beveling the ends of the bars N N so as to correspond to such formation.

It will be seen by reference to Fig. 10 that there is a short space left between the back surfaces of the gripping dies or bars G G' and the pointing-bars N N. This space gives the 120 length of nail-wire which is necessary to form a head on a nail.

I will now describe the mechanism for forming the heads on the nails and freeing the finished nails from the machine.

The header J is a straight bar arranged in the median line of the machine, and its front end is provided with a steel heading-tool of suitable shape to form at one blow the required 130 head, which tool may be removed and another substituted. The heads are formed on the nails

before the nails are pointed and separated from the wire, as before stated. The header J is endwise movable in guides q q', and its rear end is rigidly secured to a circular plate, K, to which four rods are secured by collars and nuts, as shown in Figs 1 and 4. These four rods are free to pass through a circular plate, K', to the center of which a screw, P, is attached by a swivel. Around each one of the four rods above referred to a helical spring, S, is applied, and the screw P is tapped through a cross-head, P', that is rigidly but adjustably secured by set-screws r r to parallel rods R R, which are bolted to lugs formed on the rear guide, q'. The object of the screw P is to adjust the tension of the springs S, and a hand-wheel, P², is applied on its rear end to facilitate the adjustment, and a jam-nut, t, is used to prevent it from turning by jar. The header J is moved backward by a comparatively slow motion during the feeding forward of the nail-wire by means of a toe or cam, T, keyed on the shaft B, acting on a lug, T', made fast to the header, as shown in Fig. 13. During this back-stroke of the header the four springs S will be compressed, and when the toe T slips from its lug the springs will with considerable force shoot the header forward against the protruding end of a nail-wire and form a nail-head against the two inner ends of the gripping-bars. V designates an angular lever which has its fulcrum at u. The rear end of this lever is at proper times lifted by a cam on the shaft B, which depresses its forward end and knocks the finished nail down through a hole, W, made through the bed of the frame A. A spring, S³, lifts the lever V.

It is obvious that my invention is applicable to the manufacture of spikes, rivets, and other like articles.

Having described my invention, I claim as new—

1. In a machine for making nails, the combination of a guide for the nail-wire, a rectilinear reciprocating carriage or slide, a yielding feeder and burring-wheels on this carriage, operating substantially in the manner and for the purposes described. 40

2. The combination, with the slide or carriage D, the yielding feeder, and burring devices, of the tension-spring and the adjustable nut therefor, substantially as described. 50

3. The combination of burring devices and a spring-actuated feeder with a slide or carriage, when said devices are secured to and movable with the slide or carriage, substantially as described. 55

4. In a nail-making machine of the character described, the combination of the slide D, bearing the feeder and burring devices, the grippers, the pointers, and the header, actuated as described, an adjustable wrist-pin, a connecting-rod, a rock-shaft, and a vibrating arm, substantially as described. 60

In testimony whereof I affix my signature, in presence of two witnesses, this 4th day of April, 1882.

WILLIAM TAYLOR.
